UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

ELASTIC-FLUID TURBINE.

1,218,468.

Specification of Letters Patent.

Patented Mar. 6, 1917.

Application filed October 11, 1916. Serial No. 124,976.

To all whom it may concern:

Be it known that I, RICHARD H. RICE, a citizen of the United States, residing at Lynn, county of Essex, State of Massachusetts, have invented certain new and useful improvements in Elastic-Fluid Turbines, of which the following is a specification.

The present invention relates to horizontal condensing elastic fluid turbines wherein the condenser has its casing bolted directly to the turbine casing, and has for its object to provide an improved arrangement in an installation of this type.

For a consideration of what I believe to be novel and my invention, attention is directed to the accompanying description and the claims appended thereto.

In the accompanying drawing, Figure 1 is a side elevation of a turbo-generator set embodying my invention; Fig. 2 is a top plan view of the turbine and condenser end of the set; Fig. 3 is a vertical section through one of the condenser sections; Fig. 4 is a longitudinal section on a line extending between the two condenser sections and through the center of the turbine, and Fig. 5 is an end view looking at the low pressure end of the turbine, the condenser being removed.

Referring to the drawing, 10 indicates a horizontal elastic fluid turbine which, in the present instance, is shown as driving an electric generator 11. 12 indicates the turbine shaft upon which are mounted the wheels 13 carrying rows of buckets 14. The turbine illustrated is of the impulse type and has four stages, there being a single wheel with two rows of buckets in the first stage, and a single wheel with one row of buckets in each of the other stages. The exhaust end of the turbine terminates in two rectangular openings 15 and 16, the arrangement of which is best illustrated in Fig. 5. Between these openings is a vertical wall 17 which carries a bearing 18 for the one end of the shaft 12. 19 and 20 indicate the other two shaft bearings.

The condenser comprises two condenser sections 21 and 22, each having an admission opening 23 corresponding in size and shape to openings 15 and 16. The two condenser sections are alike, one of them being shown in section in Fig. 3. It comprises a casing 24 having at its two ends the tube sheets 25 into which the condenser tubes 26 are fastened. Over the two ends of casing 24 are the heads

27 and 28, the latter having a partition 29 which divides it into two chambers. Circulating water enters by opening 30, flows up through one group of the tubes 26, then down through the other, and out by way of opening 31. 32 indicates the conduits to which the air pump (not shown) is connected for withdrawing air, gases and vapor from the condenser, and 33 the conduits to which the condensate pump (not shown) is connected. The condenser sections 21 and 22 are vertically arranged; *i. e.*, the tubes 26 are vertical, and the openings 15 and 16 in the turbine casing and the openings 23 in the condenser sections extend substantially the length of the tubes 26. This gives a path of large area for the elastic fluid exhausting from the turbine, and since the condenser casings are bolted directly to the turbine casing, the path is a short one. In fact, as will be clear, the blades of the final wheel 13 revolve at but a short distance from the tubes 26. This means that there are practically no friction losses between the turbine and the condenser and that the pressure of the final stage of the machine is substantially that of the vacuum. This results in a better efficiency of the turbine and decreased losses in the condenser system.

The turbine casing is connected to the generator 11 by a rigid frame 34, and the unit as a whole is supported by a suitable support 35 arranged beneath the generator 11, and supporting members arranged beneath feet 36 carried by the condenser sections 21 and 22. Each condenser section has preferably two feet 36 one on each side as shown in Fig. 2, and 37 (Fig. 2) indicates a common supporting member for the two feet which are adjacent each other. By this arrangement the turbine is suspended between the generator and the condenser.

38 indicates a speed governor and 39 indicates generally the valve gear for regulating the supply of elastic fluid to the turbine. It will be understood that these parts may be of any suitable structure.

By constructing the condenser in two sections, one located to each side of the center line of the machine, the bearing 18 can be located between them and directly adjacent the turbine casing. This economizes in the overall length of the machine and requires that the shaft be no longer than usual. At the same time, the bearing is readily accessible.

Also by the vertical arrangement of the condenser, the minimum amount of floor space is utilized. This vertical arrangement also has the advantage that by removing the upper heads of the condenser sections, the tubes can be removed vertically for inspection and repair. In power plants floor space is usually limited while there is plenty of over-head space. With this vertical arrangement no floor room need be provided for the removal of the condenser tubes, as is the case with the usual condenser in which the tubes are arranged horizontally. The installation accordingly will occupy less floor space than would otherwise be the case.

While I have shown the two condenser sections cast separate from the turbine casing and fastened thereto, it will be understood that I am not limited to this arrangement but may if found desirable, cast the parts integral.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:

1. The combination with a horizontal elastic fluid turbine having a casing, of a condenser therefor comprising two condenser sections fastened directly to the turbine casing, said condenser sections having

vertically arranged cooling tubes and being located one on each side of the center line of the turbine.

2. The combination with a horizontal elastic fluid turbine having a casing and a shaft, of a condenser therefor comprising two condenser sections fastened directly to the turbine casing; said condenser sections having vertically arranged cooling tubes and being located one on each side of the center line of the turbine, and a bearing for the turbine shaft located between said sections.

3. The combination with a horizontal elastic fluid turbine having a casing, of a condenser therefor comprising two condenser sections fastened directly to the turbine casing, said condenser sections having vertically arranged cooling tubes and being located one on each side of the center line of the turbine, and supporting feet carried by the condenser sections.

4. The combination with a horizontal elastic fluid turbine having a casing and a shaft, of a condenser therefor comprising two condenser sections fastened directly to the turbine casing, said condenser sections having vertically arranged cooling tubes and being located one on each side of the center line of the turbine, a bearing for the shaft carried by the turbine casing and located between the condenser sections, and supporting feet for the turbine and condenser carried by the condenser sections.

In witness whereof, I have hereunto set my hand this sixth day of October, 1916.

RICHARD H. RICE.
